Primary Examiner — Marianne Pandozzi(74) *Attorney, Agent, or Firm* — Banner & Witcoff, Ltd.(57) **CLAIM**

The ornamental design for a beverage dispenser tower, as shown and described.

DESCRIPTION

FIG. 1 is a top, front, left perspective view of a beverage dispenser tower showing our new design;

FIG. 2 is a top, rear, right perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines in the drawings are included for the purpose of illustrating environment and form no part of the claimed design.
